UNITED STATES PATENT OFFICE.

JAMES E. DEARDORFF, OF WICHITA, KANSAS.

VACUUM STREET-CLEANER.

1,168,175.

Specification of Letters Patent. Patented Jan. 11, 1916.

Application filed January 30, 1914. Serial No. 815,469.

To all whom it may concern:

Be it known that I, JAMES E. DEARDORFF, a citizen of the United States, residing at Wichita, in the county of Sedgwick and State of Kansas, have invented certain new and useful Improvements in Vacuum Street-Cleaners; and I do hereby declare the following to be a full, clear, and exact description of the invention, such as will enable others skilled in the art to which it appertains to make and use the same.

This invention relates to vacuum street cleaners and one of the principal objects of the invention is to provide a street cleaner which will pass over rough and uneven surfaces and thoroughly clean the same.

Another object is to provide a vacuum street cleaner in which the brushes and the intake nozzle are arranged in series and independently mounted, so that the brushes may yield to uneven surfaces and draw the dirt and refuse up through the intake nozzles to thoroughly clean the street.

These and other objects may be attained by means of the construction illustrated in the accompanying drawings, in which—

Figure 1 is a side elevation and partial section of a vacuum street cleaner and sprinkler made in accordance with this invention; Fig. 2 is a top plan view of the same with a portion of the sprinkler tank and sprinkler broken away, Fig. 3 is a front elevation of the same, Fig. 4 is a detail elevation and partial section of one of the intake nozzles.

In the accompanying drawings it will be seen that there are four intake nozzles, four settling tanks and vacuum chambers, and four suction fans. It will be obvious, however, that any suitable number of each of the parts referred to may be used, and it will also be apparent that since these devices are of identical construction, the description of one will serve as a description for all.

Referring to the drawings, the numeral 1 designates the vehicle body, 2 are the wheels, 3 is the motor for driving the vehicle and for operating the fans, 4 is the driver's seat, 5 is the steering wheel, and 6 is the hood extending over the driver's seat.

Mounted in a bracket 8 is the intake nozzle 9 provided with a flaring mouth 10. The rotary brushes 11 are each provided with an independent shaft 12 and each of these shafts is mounted in brackets 13. Also

mounted in the brackets 13 are the axles 15 of the wheels 14, which run upon the ground. The axles are supported on the nozzles 9. The brackets 13 have one end mounted on the shaft or axles 15 and their opposite ends secured to the brushes 11 by a shaft 12. Sprocket wheel 16 is mounted on the shaft 15 and a sprocket wheel 17 is mounted on the shaft 12 and a chain 18 connects said sprocket wheels to rotate the brush 11 as the wheels 14 pass over the ground. The intake nozzles 9 are each mounted telescopically in the suction pipe 7 and will thus conform to the uneven surface of the street by gravity.

Each of the pipes 7 leads up and into a refuse chamber 19 and as shown in Fig. 2 there are four of these chambers of like construction. Each of the refuse chambers 19 is provided with a clean-out cap 20 at its lower end and a depending discharge pipe 21 which communicates with the refuse chamber 19 at one side near the upper end thereof.

The discharge pipe 21 extends into the settling chamber 22, said settling chamber having a quantity of water 23 therein. The lower end of the discharge pipe 21 carries a perforated enlargement 24 which is disposed normally below the water line in the tank 22. Above the water line in the tank 22 is a vacuum chamber 25, and a curved pipe 26 connects the vacuum chamber with the fan casing 27. An outlet pipe 28 is connected to the opposite side of the fan casing from the pipe 26. A gasoline tank 29 is mounted on the settling tanks for supplying fuel to the motor.

At the rear of the machine is mounted a water tank 30 having a sprinkling tube 31 at its lower outer side and a filling cap 32 at its upper side.

A drive chain 32 is actuated from the motor shaft and passes around a sprocket wheel 33 on a shaft 34 mounted underneath the frame of the machine. A sprocket chain 35 leads around a sprocket wheel on the shaft 34 and around a similar sprocket 36 on the shaft 37 mounted underneath the frame of the machine. A sprocket chain 38 leads around a similar sprocket on the shaft 37 and around a sprocket 39 on a shaft 40 mounted in the frame. A chain 41 leads around a sprocket wheel 42 on the shaft 40 and around a sprocket wheel 43 on the rear axle of the machine. A drive

chain 38^a is used for each fan casing 27, said chains passing over sprocket wheels on shaft 37 and around sprocket wheels on the fan shafts.

5 The operation of the cleaner may be briefly described as follows: As the machine moves along the street or road, the rotary brushes 13 loosen the refuse and dirt from the street and present it to the mouths 10
10 of the vacuum nozzles, and since each of these nozzles is independently mounted they will rise and fall to conform to the undulating surface of the street and to pass over obstructions too large to be drawn up into
15 the nozzle. The dirt and refuse is drawn up through the pipe 7 into the refuse chamber 19 by means of the suction fan. The discharge pipe 21 discharges into the water 22, and the fan draws the air through the
20 chamber 25 and the pipe 26 and discharges it through the outlet pipe 28.

The sprinkler follows the cleaning operation and prevents the dirt from rising following the action of the machine.

25. Various changes in the details of construction may be resorted to without departing from the spirit and scope of the invention as defined in the claims.

What is claimed is:—

30. 1. A vacuum street cleaner comprising a suction pipe, an intake nozzle mounted on

said pipe, a shaft extending through said nozzle, ground wheels mounted on the ends of said shaft outside of the nozzle, brackets extending forwardly from the ends of said shaft, a rotary brush, said brush mounted on the forward ends of said brackets, a sprocket wheel mounted on one end of said shaft, a sprocket wheel mounted on one end of said brush, and a sprocket chain connecting said sprocket wheels.

2. A vacuum street cleaner comprising intake nozzles, a pipe leading from each of said nozzles, and mounted in a suction pipe telescopically to permit independent movement of each nozzle, a shaft mounted transversely in each of said nozzles and projecting beyond on both sides, ground wheels mounted on the ends of said shafts, brackets extending forwardly from the ends of said shafts, rotary brushes, said brushes mounted on the forward ends of said brackets, means for rotating the brushes from said wheels, a refuse chamber communicating with said pipes and a suction fan communicating with said chamber. 45 50 55

In testimony whereof I affix my signature
in presence of two witnesses.

JAMES E. DEARDORFF.
